UNITED STATES PATENT OFFICE

ANGUS N. McDONALD, OF DETROIT, MICHIGAN, ASSIGNOR TO DETROIT SHOW CASE COMPANY, A CORPORATION OF MICHIGAN

STORE FRONT SASH

Application filed October 10, 1930. Serial No. 487,837.

My invention relates to a supporting structure for large plate glass panes and has particular reference to what is termed the sash portion of such a structure, this portion forming the supporting base of positioning the window panes of large display windows.

An object of my invention is to facilitate the installation of large plate glass panes in store fronts, and the like, at the same time providing a structural element which is artistic and which may be made in conformity with any desired type of architecture.

A more specific object is to eliminate all surplus elements which customarily form portions of the built up composite metal window sash for such glass plates and to provide a construction which embodies a minimum number of cooperating elements which may be quickly positioned with respect to one another and readily secured in position to properly support a plate glass in a manner superior to what has heretofore been available.

In suggesting a specific use for my improved structure, I contemplate primarily its use in conjunction with store fronts and an important object resides in rendering the structural elements architecturally beautiful, simple and practical to install, and as inexpensive to manufacture as possible.

Various other objects and meritorious features of my invention will be apparent from the following description taken in conjunction with the drawing, wherein like numerals refer to like parts throughout the several figures and wherein:

Fig. 1 illustrates in perspective what I shall hereafter term the face plate of my composite structure.

Fig. 2 illustrates in perspective what I shall term the set plate thereof,

Fig. 3 is a section of my improved structure after assembling and,

Fig. 4 illustrates a modification of the assembly shown in Fig. 3.

Referring to the drawing the face plate, which I have broadly designated by the numeral 10, includes a channel shaped bottom portion 12, the lower wall 14 of which channel is adapted to seat upon a supporting frame 16 such as the sill or jamb. The face

of the plate may be designed with any desired configuration, and rolled to provide any desired ornamental features such as the stepped-in portion 16. The upper portion of the face plate consists also of a channel shaped portion 20, the inner wall 22 of which constitutes a positioning surface for the glass pane which is to be utilized.

Depending from the wall 22 along the length thereof is a third channel shaped portion 24, somewhat offset from the perpendicular and extending forwardly toward the front of the face plate as clearly illustrated. The inner wall 26 of this depending channel shaped portion, and the bottom wall 14 of channel portion 12 are designed to co-operate, in a manner to be described, with the set plate.

The bottom of channel shaped portion 24 is cut away as at 28 at spaced apart intervals along the length of the unit and elongated slots 30 are provided between the cut away portions.

The set plate which I shall broadly designate by the numeral 32 comprises a bottom set portion 34 which is adapted to rest upon the supporting surface 16, and includes a raised lip portion 36 which is adapted to seat upon the bottom wall 14 of face plate channel 12. The bottom portion 34, on assembling the structure, may be secured to the support surface 16 by any desired means, such as the wood screw 38. The rear wall 40 of set plate 32 preferably extends vertically, altho this is not essential, and is provided along its uppermost extremity with a turned over portion 42 which is adapted to firmly position the rear wall 26 of the channel shaped portion 24 of the face plate.

It will be understood that in the structure illustrated in Figs. 1, 2 and 3, the set plate will first be positioned upon the supporting surface 16 and the face plate subsequently positioned. Supporting blocks 43 are inserted in the openings 28 and along the top of these is seated a strip 44 of some material particularly adaptable to constitute a seat for edge of a glass plate. While no particular material need be specified herein, lead is quite frequently used for this purpose.

The set plate 32 includes the gutter like portion 48 and the rear positioning surface 50, which later cooperates with face 22 of the face frame 10 to position the glass plate 46.

5 The glass pane is positioned upon the supporting blocks 43 after the set plate is installed and thereafter the face plate is disposed in place.

10 At spaced apart intervals along the bottom of gutter like portion 48 there are apertures 52 which are so spaced that they are each adapted to cooperate with slots 30. To secure the assembly in position it is only necessary to insert screw 54 in apertures 52 and, by virtue of the elongated slots 30, the extremities of these screws 54 will always find an opening in the face plate 10 whereby the two plates may be secured together. Obviously this constitutes a substantial improvement over such structures as provide a plurality of apertures such as 52 in each of the plates, wherein the apertures must be accurately aligned before the screw 54 may be tightened.

25 By virtue of the angular position of securing screws 54 it will be apparent that the tightening up operation will draw the face portions 22 and 50 of the two plates respectively firmly against the sides of the glass pane 46.

30 The gutter 48 functions as an effective drain for any moisture which may accumulate at the base of the window pane. Drainage holes 49 are provided in the gutter 48 and weep holes 15 are provided in the base 35 channel of the face plate. These holes also afford ventilation for the usual purposes. The use of elongated slots 30 materially decreases the time necessary for assembling the structure inasmuch as there is no necessity 40 for feeling about to accurately align two thread apertures, and it will be apparent from Fig. 3 that the set plate bears firmly upon the face plate along its bottom and top 45 extremities, which also constitute the front and rear extremities.

In the setting up of my assembly the edge 50 of the flange 26 seats between the wall 40 and overhang 42 of the set plate so that the tightening of the screws exerts a tension through the channel 24 to urge the face 22 of the face plate toward the flange 50 of the set plate.

55 A distinct advantage of my structure resides in the fact that the complete assembling operation may be performed from within and that the fastening means do not extend through the front face of the structure. The tightening screws 54 are inserted and tightened from the rear after the assembly is in position.

A somewhat modified structure is illustrated in Fig. 4 wherein the bottoms 56 of the face plate is provided with a raised lip 58 at its rear extremity, this lip being adapted to

bear down upon the bottom supporting surface 60 of the set plate. In this instance the face plate will first be secured in position and the set plate subsequently positioned. The glass pane 46 is inserted as hitherto described and the screws 62 utilized in the same manner as hitherto described to tighten the assembly in position.

Having illustrated, with modifications, my improved structure, various other modifications will be apparent to those skilled in the art and for that reason I intend to limit myself only within the scope of the appended claims.

What I claim is:

1. A glass pane supporting structure comprising, in combination; a face plate having a supporting base, a glass pane positioning surface at its upper extremity, and a channel shaped portion depending therefrom; and a set plate adapted to cooperate with said supporting base and channel shaped portion to secure the same in fixed position, said set plate including a positioning surface adapted to align in parallel spaced relation with the positioning surface of the face plate.

2. A plate glass supporting structure comprising, in combination, a face plate, and a set plate adapted to seat upon said face plate along its front and rear extremities whereby the two plates are positioned with respect to one another, and means operable from the rear of said assembly to secure said elements in position.

3. A plate supporting structure comprising, in combination, a face plate including a positioning surface extending along its upper edge, a channel depending therefrom, a set plate adapted to seat upon the base of said face plate along the length thereof and upon the inner wall of said channel portion, and means for securing said plates in position from the rear thereof.

4. A plate supporting structure comprising, in combination, a face plate including a positioning surface along the upper edge thereof and a depending channel shaped portion depending rearwardly thereof, said channel being cut away at spaced apart intervals along its length, elongated slots in the bottom of said channel, and a set plate adapted to cooperate with said face plate to position the same, said set plate including a positioning surface extending along its upper edge and adapted when positioned to align in spaced parallel relation with said first mentioned positioning surface, and a gutter like portion rearwardly of said positioning surface, said gutter portion including spaced apart apertures adapted to align with said elongated slots.

5. A plate supporting structure comprising, in combination, a face plate including a flanged base extending along the bottom thereof, a channel shaped positioning sur-

- face extending along the upper edge thereof, and a channel shaped portion depending angularly from said positioning surface, and a set plate including a base portion provided 5 with a projecting raised lip adapted to seat along said flanged base, said set plate being provided along its upper edge with a gutter, the inner wall of which is adapted to lie in parallel spaced apart relation with the positioning surface of said face plate, and means for securing said plates together from the rear thereof.
6. A plate supporting structure comprising, in combination, a face plate including a flanged base extending along the bottom thereof, a channel shaped positioning surface extending along the upper edge thereof, and a channel shaped portion depending angularly from said positioning surface, said channel shaped portion being cut away at spaced apart intervals and provided with elongated slots between said cut away portions, and a set plate adapted to seat along the lower and upper extremities of said face plate and including a positioning surface extending along its upper edge in spaced parallel relation to the positioning surface of said face plate, and spaced apart apertures to the rear of said set plate positioning surface adapted 20 to align with said elongated slots.
7. A store front construction comprising, in combination with a glass pane, a face plate having a surface engaging one face of the pane and a channel depending from said surface underneath the edge of the pane and having a bottom provided with spaced apart slots, a set plate cooperating with the face plate having a surface engaging the opposite face of the pane and having a gutter provided with spaced apart apertures, and fastening means extending through said apertures and slots securing the glass pane engaging surfaces of said plates against said pane.
8. A store front construction comprising, in combination with a glass pane, a face plate having a surface engaging one face of the pane and a channel depending from said surface underneath the edge of the pane having a bottom provided with spaced apart slots, a set plate cooperating with the face plate having a surface engaging the opposite face of the pane and having a gutter provided with spaced apart apertures superimposing said slots, said gutter having a portion seating upon a part of the channel of the face plate, and securing means extending through said apertures and slots holding said face plate and set plate against opposite faces of the glass pane.
9. A store front construction comprising, in combination with a glass pane, a face plate having a surface engaging one face of the pane and a flange extending underneath the edge of the pane and provided with spaced apart apertures to receive pane supporting elements and also provided with spaced apart slots, pane supporting elements positioned within said apertures, a set plate having a gutter superimposing in spaced relationship 50 the flange of said face plate and provided with a surface engaging that face of the pane opposite the face engaged by the face plate and provided with apertures corresponding with the slots in the face plate, and fastening elements extending through said apertures and slots holding said face plate and set plate snugly against opposite sides of glass pane.
10. A store front construction comprising, in combination with a glass pane, a face plate having a surface engaging one face of the pane and a part extending underneath the edge of the pane provided with spaced apart slots, a set plate provided with a surface engaging the opposite face of the pane and provided with apertures corresponding with said slots, and fasteners extending through said apertures and slots holding the pane engaging surfaces of said plates against opposite sides of the glass pane.
11. A store front construction comprising, in combination with a glass pane, a face plate engaging one face of the pane and having a part extending underneath the edge thereof and provided with slots on the opposite side of the pane, a cooperating set plate engaging the opposite face of the pane and provided with a part having apertures corresponding with said slots, and screws received through said apertures and engaged in the slots holding said plates against opposite sides of the pane.
12. In store front construction, in combination with a glass pane, a face plate engaging one face of the pane and having a channel extending underneath the edge of the pane and provided with apertures, a set plate engaging the opposite face of the pane and having a channel received within the channel of the face plate and provided with apertures corresponding with the apertures in the channel of the face plate, and fastening means extending through said apertures and securing said plates against opposite sides of the pane.
13. In store front construction, in combination with a glass pane, a metal sash structure comprising a face plate engaging one face of the pane and having a channel extending underneath the edge thereof, a set plate engaging the opposite face of the pane and having a channel disposed in spaced relationship within the channel of the face plate, and securing means extending through said channels holding said plates snugly against opposite faces of the glass pane.
14. A metal window sash for a glass pane comprising, in combination with the pane, cooperating sash members engaging opposite faces of the pane and provided with cooper-

ating channel portions one of which extends underneath the edge of the pane and means extending through the bottom of the channels holding said members against the opposite faces of the pane.

15. A metal window sash for a glass pane, comprising, in combination with the pane, cooperating sash elements engaging opposite faces of the pane, one of said elements having a downwardly turned portion extending underneath the edge of the pane, and means carried by the other element engaging said downwardly turned element to hold said elements snugly against opposite face of the pane.

16. A metal window cash for a glass pane comprising, in combination with the pane, cooperating pane engaging elements arranged on opposite sides of the pane and engaging its opposite faces, a channel portion carried by one of said elements and extending underneath the edge of the glass pane and engaging the opposite element, and means securing said channel shaped portion to said other elements to urge said two elements against the opposite faces of the glass pane.

17. A metal window sash for a glass pane comprising, in combination with the pane, cooperating pane engaging elements arranged on opposite sides of the pane and engaging its opposite faces, spaced apart channel portions carried by one of said elements and extending underneath the edge of the glass pane and engaging the other element on the opposite side of the glass pane and securing means securing said other element to said channel shaped portions.

18. A metal window sash for a glass pane comprising, in combination with the pane, cooperating pane engaging elements arranged on opposite sides of the pane and engaging its opposite faces, spaced apart channel portions carried by one of said elements and extending underneath the edge of the glass pane and engaging a concealed part of said other element and securing means connecting said other element with said channel shaped portions to hold said elements toward said glass pane.

19. In store front construction, in combination with a glass pane, a sash assembly comprising a face plate having a part engaging one face of the glass pane, a set plate having a part engaging the opposite face of the glass pane, spaced apart depending angular portions carried by said face plate and extending underneath the edge of the glass pane, and securing means connecting said set plate with said depending angular portions to hold said face plate and said set plate against opposite faces of the glass pane.

20. In store front construction, in combination with a glass pane, a cash assembly comprising a face plate having a part engaging one face of the glass pane, a set plate having

a part engaging the opposite face of the glass pane, angular elements arranged in spaced apart linear relationship along said face plate and carried thereby and extending underneath the edge of the glass pane and engaging said set plate, and means securing said set plate to said angular elements to hold said face plate and set plate against opposite faces of the glass pane.

21. In store front construction, in combination with a glass pane, a sash assembly comprising a face plate having a part engaging one face of the glass pane, a set plate having a channel portion one side wall of which engages the opposite face of the glass pane, an angular element carried by said face plate extending underneath the edge of the glass pane and engaging the opposite side wall of the channel portion of the set plate, and securing means connecting the bottom of the channel portion of the set plate with said angular elements to hold said face plate and set plate against opposite faces of the glass pane.

22. In store front construction, in combination with a glass pane, a sash assembly comprising a face plate having a part engaging one face of the glass pane, a set plate having a part engaging the opposite face of the glass pane and provided with an aperture for a securing member, and means extending underneath the edge of the glass pane connecting said face plate and set plate together and provided with a longitudinal slot registering with the aperture through the set plate and a securing member extending through said aperture and slot to hold said face plate and set plate together.

In testimony whereof, I, ANGUS N. McDONALD, sign this specification.

ANGUS N. McDONALD.
